UNITED STATES PATENT OFFICE.

WILLIAM MAYNARD, OF BOSTON, MASS., ASSIGNOR, BY MESNE ASSIGNMENTS,
TO WILLIAM MAYNARD AND HENRY MORTIMER, OF SAME PLACE.

SIGHT FOR FIRE-ARMS.

SPECIFICATION forming part of Letters Patent No. 318,999, dated June 2, 1885.

Application filed March 23, 1885. (No model.)

To all whom it may concern:

Be it known that I, WILLIAM MAYNARD, of Boston, in the county of Suffolk, of the Commonwealth of Massachusetts, have invented a new and useful Improvement in Sights for Fire-Arms; and I do hereby declare the same to be described in the following specification and represented in the accompanying drawings, of which—

10 Figure 1 is a top view, Fig. 2 a front elevation, Fig. 3 a rear end view, and Fig. 4 a longitudinal section, of a foresight with its tube-sight and eye-piece in accordance with my invention, such figures showing the parts 15 on an enlarged scale, or double that on which they are generally constructed. Fig. 5 is a side view of the eye-piece as separated from the tube-sight. Fig. 6 is a side view, and Fig. 7 is a rear end view, of the foresight. 20 Fig. 8 is a side view, Fig. 9 a top view, Fig. 10 an under side view, and Fig. 11 a rear end view, of the tube-sight. Fig. 12 is a transverse section of the foresight and tube-sight, such section being taken through their connecting-screw.

The nature of my invention is defined in the claims hereinafter presented.

In such drawings, the foresight of a rifle is shown at A as consisting of a flat base, a, 30 dovetailed in transverse section, a tenon, b, extending upward from such base at its middle, and a thin quadrantal projection, c, extending upward from the said tenon.

The tube-sight (shown at B) consists of a 35 short tube, d, fixed to a base, e, which has at its middle a mortise, f, to receive the tenon b. A screw or pin, g, goes laterally through the base e and the said tenon b, and serves to couple the tube-sight to the foresight when 40 the latter is in place on the front part of a rifle-barrel. The said tube d has in it a transverse slot, h, that extends from the top of the tube down to or about to a level with the axis of the tube. This slot is to receive the eye-piece C that, formed, as represented in the drawings, is slipped into the slot until the shoulders i of such eye-piece rest on the ends of the slot, in which case the little eye, k, of the

eye-piece will be brought into its correct position in the tube d. The said eye-piece C 50 consists of two circular rings, k and l, connected by a radial arm, m, the outer ring, l, having shoulders i, arranged with or formed in it as represented. A turn-button or arm, D, arranged on the top of the tube d and pivoted thereto, serves, when turned across the top of the eye-piece C, to keep such eye-piece in place 55 in the slot h.

From the above it will be seen that the tube-sight can be readily connected with or disconnected from the foresight, and may be used with it as occasion may require either with or without the eye-piece.

When the eye-piece is within the tube-sight, the radial arm m comes directly in front of the 65 projection c, and the inner ring, k, of the eye-piece extends above such projection.

I claim—

1. The combination of the tube-sight, slotted transversely, as described, with an eye-piece, 70 substantially as represented, extended into the slot, such tube-sight being provided with a device or turn-button pivoted to it and arranged with its slot, and adapted to swing over it in order to secure the eye-piece in 75 place, as set forth.

2. The combination of the eye-piece, substantially as described, having shoulders i, and consisting of two concentric rings and their connection-piece, with a slotted tube-sight and 80 a foresight, as represented.

3. The combination of the tube-sight, slotted transversely and having a mortised base, and adapted to swing over it in order to secure the eye-piece in place, as set forth, with the foresight having a tenon to extend into the mortise of the base, and a pin to go through the base and tenon, and with an eye-piece, substantially as represented, extended into the slot, such tube-sight being provided with a device or turn-button pivoted to it and arranged 85 with its slot, as set forth.

WILLIAM MAYNARD.
